(57) CLAIM

The ornamental design for an acrylic paint organizer bag, as shown and described.

DESCRIPTION

FIG. 1 is a perspective view of an acrylic paint organizer bag, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view showing the acrylic paint organizer bag, in opened state.

All the broken lines in the drawings depict portions of the acrylic paint organizer bag that form no part of the claimed design.
